UNITED STATES PATENT OFFICE

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE

SEWING MACHINE

Application filed July 17, 1924, Serial No. 726,535. Renewed April 23, 1927.

This invention relates to sewing machines of that class which are used for making a line of reinforcing stitching for reinforcing fabric at some point, such for instance as at the end of a buttonhole or at the end of a pocket slit in garments or any other similar places where a so-called "tack" or reinforcing stitching is desired. Sewing machines adapted for this purpose are sometimes referred to as "tackers."

The present invention relates to that class of "tackers" which make a line of reinforcing stitching that comprises a series of relatively long stitches extending from one end to the other of the bar or tack to be formed and another series of shorter stitches which extend transversely of the long stitches and overlie the latter. The first mentioned stitches are sometimes referred to as the "underlying" stitches or as the "long" stitches and the second group of stitches are sometimes referred to as the "overlying" stitches or as the "cross" stitches since they overlie the long stitches and also extend across or transversely thereto.

The object of my invention is to provide a sewing machine of this type which has various novel features all as will be more fully hereinafter set forth and then pointed out in the appended claims.

In the drawings:

Fig. 1 is a side view of a sewing machine embodying my invention with the cover plate removed to show the actuating mechanism;

Fig. 2 is a section on substantially the line 2-2, Fig. 1;

Fig. 3 is a vertical section on substantially the line 3-3, Fig. 2;

Fig. 4 is a horizontal section on substantially the line 4-4, Fig. 1;

Fig. 5 is a horizontal section showing a portion of the stop mechanism;

Fig. 6 is a section on substantially the line 6-6, Fig. 1;

Fig. 7 is a horizontal section on substantially the line 7-7, Fig. 1;

Fig. 8 is a sectional view showing the manner of clutching the long stitch cam to the driving shaft;

Fig. 9 is a section on the line 9-9, Fig. 1 illustrating the short stitch cam;

Fig. 10 is a section on the line 10-10, Fig. 1;

Fig. 11 is a detail of the stop mechanism;

Fig. 12 is a section showing the clutch for clutching the short stitch cam to the drive shaft;

Fig. 13 illustrates the form of stitch which is made by the sewing machine;

Figs. 14 and 15 are fragmentary detail views of the stop motion;

Fig. 16 is a detail view showing the operation of the feed cam 71;

Figs. 17 and 18 are sectional views illustrating the manner in which the long stitch cam is unclutched from the driving shaft;

Fig. 19 is a fragmentary view showing the clutch-controlling means for the short-stitch cam;

Figs. 20 and 21 are views illustrating the clutch for the long-stitch cam.

The type of stitching which is made by the sewing machine is illustrated in Fig. 13 and it comprises a plurality of long or underlying stitches 1 and a plurality of short or overlying stitches 2 that extend transversely of the stitches 1.

The operative parts of the sewing machine are supported in a suitable frame 3 which is formed with a laterally-extending arm 4 on which is supported work clamps 5 in which the work is held, said frame being also formed with the overhanging arm 6 in which reciprocates the needle bar 7 carrying the needle 8.

The needle operates in a fixed vertical path and the stitching is formed by giving the work clamps 5 a vibrating movement. The work clamps are given a long vibrating movement in one direction to form the long stitches 1 and then are given a shorter vibrating movement in another direction to form the short stitches 2 and while the short stitches are being formed the feed clamps are also given a feeding movement in the direction of the long stitches so that the short stitches will extend from one end to the other of the long stitches.

The arm 4 also forms at its end a support

for the under thread mechanism which is in the form of a shuttle or hook of any usual construction which may be indicated generally at 9.

5 The machine is driven from a driving pulley 10 which is adapted to be clutched to a driving shaft 11 by means of a suitable clutch controlled by a clutch cone 12 that is slidably mounted on the driving shaft. The 10 movement of the cone 12 to the left Fig. 3 throws the clutch into operation and when the cone is in the position shown in Fig. 3 the clutch is disengaged. This clutch cone is actuated by a clutch rod 13 slidably mounted in the frame and provided with a spring 14 which normally holds it in its inoperative position. It is thrown into its operative position to clutch the pulley to the shaft by means of a lever 15 pivoted at 16 to the 15 frame and adapted at one end to engage the rod 13 and at the other end connected to a suitable treadle by a link 17.

The shaft 11 is geared to a needle-actuating shaft 18 by suitable gearing 19, said 20 shaft 18 extending longitudinally of the head 6 and being operatively connected to the needle bar in any approved way.

25 The hook or shuttle is actuated from a rock shaft 20 which has a crank arm 21 thereon 30 that is connected by a link 22 to a crank 23 on the shaft 18.

The work clamp 5 comprises two clamping members 24, 25 which can be opened to receive the work between them, the member 35 25 having the resilient shank 26 which yielding 40 holds the upper clamp clamped against the work. The clamp may be opened by means of a lever 27 pivoted at 28 and connected to the upper clamp by a link 29. The work clamp is pivoted to the arm 4 at 30 and the oscillating movement of the work clamp about the pivot is that which produces the 45 long stitches. The work clamp can also vibrate longitudinally of the arm and this is the vibration which is given to it during the formation of the short stitches.

50 The oscillating movement of the work clamp during which the long stitches are formed is derived from a long-stitch cam and the other movement of the work clamp during which the short stitches are formed is produced by a short-stitch cam. These cams are mounted on a vertical cam shaft 31 which is supported in suitable bearings in the frame and which is driven from the shaft 18 through a suitable worm gear 32.

55 The long-stitch cam by which the long stitches 1 are formed is indicated at 33. It 60 is provided with a cam groove 34 in which operates a roll 35 carried on the end of an arm 36 that is fast on a vertically-extending rock shaft 37, said rock shaft having an arm 38 extending therefrom which is connected to the rear end of the work clamps. The 65 cam groove 34 gives an oscillating movement

to the arms 36 and 38 and such oscillating movement is transmitted to the work clamp thereby oscillating it about its pivot 30. The connection between the arm 38 and the work clamp is an adjustable one to provide for making underlying stitches of different lengths.

70 As herein shown the arm 38 is formed with a slot 39 in which is adjustably mounted a connecting block 40, the latter having a stud 41 which operates in a groove 42 formed in the rear end 43 of the work clamp. This connection provides for transmitting the oscillating movement of the arm 38 to the work clamp and by adjustment of the block 40 provision is made for varying the amplitude of oscillating movement of the work clamp and thus the length of the long stitches 1.

75 When the machine is started in operation the long-stitch cam 33 will make one revolution and then will be automatically brought to rest at which time the short-stitch cam, presently to be described, will be set in operation to produce short stitches 2. The long-stitch cam is loose on the cam shaft 31 but it is adapted to be clutched thereto by a clutch pin 44 which is slidably vertically through the cam member 33 and is adapted to engage in a notch or recess 45 formed in a collar 46 that is fast on the cam shaft 31. This clutch pin 44 is acted upon by a spring 47 which holds it yieldingly in its operative position.

80 The means for disconnecting the clutch pin 44 from the collar 46 when the long-stitch cam 33 has made one complete revolution comprises a disengaging lever 48 pivotally mounted on a vertical shaft 49 and provided with a cam nose 50 adapted to co-operate with a cam surface 51 formed on the head of the pin 44.

85 When the cam surface 51 rides up on the cam surface of the nose 50 the clutch pin 44 will be raised against the action of the spring 47 and thereby withdrawn from the socket 45, which action will unclutch the long-stitch cam from the driving shaft 31.

90 At the time that the long-stitch cam is thus unclutched the short-stitch cam is automatically clutched to the cam shaft 31.

95 The short-stitch cam is indicated at 52 and it acts on a roll 53 carried by one arm of an elbow lever 54 which is mounted to turn on the rod 49, the other arm of said lever being connected by a link 55 to the rear end 43 of the work clamp. This roll 53 is normally held against the cam by means of a spring 56 and the co-operation of said spring and the cam 52 will give the lever 54 an oscillating movement which will produce a reciprocating movement in the work clamp in the direction of the length of the arm 4. The cam 52 is clutched to the shaft 31 through the medium of a clutch device 100 105 110 115 120 125 130 135 140 145 150 155 160 165 170 175 180 185 190 195 200 205 210 215 220 225 230 235 240 245 250 lustrated best in Fig. 12 and which comprises a clutch pin 56 carried by the cam member and adapted to enter in one of a plurality of recesses or notches 57 in a clutch collar 58 which is splined to the shaft 31 and is movable vertically thereon. This clutch collar 58 is controlled from the long-stitch cam 33 in such a way that when the long-stitch cam is automatically disengaged the clutch collar 58 is shifted to clutch the short-stitch cam 52 to the shaft 31.

The long-stitch cam 33 is formed with a depending cam rib 59 which is provided with a notch 60. Pivoted to the frame at 61 is an arm 62, the nose 63 of which travels on the cam rib 59. This arm has connected thereto a link 73 which carries a pin 64 provided with a roll 65 that operates in a groove 66 formed in the clutch collar 58. The lower end of the link 73 is provided with a slot 67 in which is received a guide pin or screw 68 carried by the bearing 69.

70 indicates a spring acting on the lower end of the link and tending to move it upwardly, said spring operating to hold the nose 63 against the cam rib 59. When the nose is on the high part of the cam rib, as shown in Fig. 19, the clutch collar 58 will be in its lowered position and the short stitch cam 52 will be disconnected from the shaft 31. This is the position of the parts while the long-stitch cam 33 is rotating and forming the long stitches 1. When the long-stitch cam has completed its rotation and the long stitches 1 are all formed the notch 60 is at that time in line with the nose 63 of the lever 62 and said nose will enter the notch under the influence of the spring 70 thereby raising the link 73 and raising the clutch collar 58 into the position shown in Fig. 12, thereby clutching the short-stitch cam 52 to the shaft 31. As soon as this occurs the work clamps are given a reciprocating movement of relatively short amplitude in the direction of the length of the arm 4 thereby to form the short stitches 2.

During the formation of the short stitches 2 the work clamps 5 have a feeding movement in the direction of the long stitches 50 so as to carry the short stitches from one end to the other of the bar. This feeding movement is controlled by a feed cam 71 that is loosely mounted on the shaft 31 and is actuated at the proper time.

The feed cam co-operates with one arm of an elbow lever 72 which is loosely mounted on the shaft 49 and the other arm 74 of which engages a pin 75 rising from the end 43 of the work clamp. When the long stitches 1 have been completed the work holder is at one end of its stroke and in the full line position shown in Fig. 16. At this time the feed cam 71 is moved into a position in which it will engage the elbow lever 72, said lever resting against the high point of the

cam. The cam is then fed forwardly with a slow movement into the dotted line position Fig. 16 and during this forward movement the elbow lever 72 will ride down the face of the cam and the work clamps will be moved from the full to the dotted line position Fig. 16. This feeding movement of the work clamps occurs while the short-stitch cam is operating and by this means the short stitches 2 are carried from end to the other of the bar and the work clamps are returned to the initial position which they occupied at the beginning of the sewing operation.

The means by which the feed cam 71 is operated will now be described. This cam is loosely mounted on the driving shaft 31 and is acted on by a spring 84 which normally tends to turn the cam from the dotted line position to the full line position Fig. 16. The cam 71 has rigid therewith a ratchet member 76 which is fed forward at proper times by means of feed pawls 77 carried on a pawl carrier 78 that is mounted to oscillate about the shaft 31. This feeding movement of the ratchet which is derived from the feed pawls 77 turns the ratchet and cam anti-clockwise in Fig. 16 or in opposition to the spring 84.

It will be remembered that when the long stitches 1 have been completed the cam 71 is in the full line position shown in Fig. 13 and as the short-stitch cam is set in operation to form the short stitches the feed cam 71 is given a slow feeding movement by the pawls 77 from the full line position around into the dotted line position Fig. 16. During this feeding movement of the cam 71 the work clamps are acted on by a spring, which will be presently described, tending to swing them from the full line position to the dotted line position Fig. 16, this spring holding the pin 75 against the arm 74 of the lever 72 and also holding said lever 72 against the cam 71. Therefore, as the cam 71 is fed forward by the pawl 77 and ratchet 76 the lever 72 will follow down the cam and the work clamp will swing slowly about its central pivot 30 under the influence of the above-mentioned spring thereby slowly feeding the work clamps from one end to the other of the long stitches.

The pawl carrier 78 is connected by a link 79 to the long arm 80 of the elbow lever 54. The pawl carrier 78, therefore, oscillates with the lever 54 and at each forward movement of said lever and pawl carrier the ratchet 76 and cam 71 will be fed forward one step provided the pawls are in mesh with the lever. This forward feeding movement of the cam 71 is in opposition to the action of the spring 84 above referred to. This spring is in the nature of a spiral spring, one end of which is connected to the cam 71 and the other end of which is connected to the frame at 85. This spring 84 is thus wound up or placed under tension as the cam 71 is fed from the full line

position Fig. 16 around to the position shown in Fig. 6.

The ratchet and cam are normally held against return movement under the action of the spring by means of a stop member or brake 81 which engages the ratchet teeth and is carried by an arm 82 extending from a yoke 83 which is loosely mounted on the shaft 37.

It will thus be seen that at the end of the formation of the long stitches 1 and at the beginning of the short stitches 2 the cam 71 is in the full line position Fig. 16 and the work clamps are also in the full line position, the last penetrating thrust of the needle being at the upper end of the tack or bar. As the short stitches are formed the cam 71 is fed forwardly by the pawls 77 into the dotted line position Fig. 16 and during this movement of the cam the lever 72 rides down the cam face and the clamps move gradually from the full to the dotted line position thus moving the work so that the short stitches will be carried from one end to the other of the tack. As soon as the short stitches 2 have been completed the machine is brought to rest by means which will presently be described. The means for oscillating the pawl carrier 78 is constructed so that the amplitude of oscillation may be varied, this resulting in varying the rate of movement of the feed cam and consequently both the spacing of the overlying stitches and the number of said stitches for any given length of underlying stitch. As shown in Fig. 6 the arm 80 is provided with a slot 180 and the end of the link 79 is adjustably secured in said slot. Since the arm 80 has a fixed amplitude of movement the adjustment of the link 79 in the slot 180 will result in varying the amplitude of oscillation of the pawl carrier 78 and thereby the rate at which the feed cam 71 is operated. If the speed of operation of the feed cam is increased the spacing of the overlying stitches will be greater and there will be fewer of said stitches for a given length of underlying stitch but if the speed of the feed cam is reduced then the spacing of the overlying stitches will be less and the number of overlying stitches will be greater.

This adjustment, therefore, constitutes means whereby the number and spacing of the overlying stitches may be adjusted and such adjustment is entirely independent of the adjustment of the block 40 by which the length of the underlying stitch is adjusted.

During the feeding of the feed cam 71 from the full to the dotted line position Fig. 16 the spring 84 is wound up. Means are provided whereby as soon as the long stitches are begun on the next succeeding tack the pawls 77 will be released from the ratchet 76 and will be held released while the long stitches are being formed. The cam 71, however, is prevented from being returned to the full

line position under the influence of the spring 84 by a stop member or brake 81, and means are provided for releasing this brake just before the long stitches 1 are completed so that the cam 71 will be positioned in its full line position Fig. 16 by the spring 84 just before the beginning of the short stitches 2.

The releasing of the pawls 77 is controlled from the long stitch cam 33 through the lever arm 62. This arm is fast on a rock shaft 86 journalled in suitable bearings 87 and said rock shaft has also fast thereon an arm 88, the lower end of which engages a projection 89 formed on a pawl-releasing plate 90. This pawl-releasing plate is situated beneath the pawl actuator 78 and is provided with pins 91 which extend through slots 92 formed in the actuator and which are adapted to engage the pawls 77.

The pawl-releasing plate 90 can move back and forth on the actuator and is guided in its movement by guide pins 93 carried by the pawl actuator and operating in slots 94 formed in the pawl-releasing plate 90. This pawl-releasing plate and the pawl actuator are connected by a spring 95 which normally tends to hold them in the position shown in Fig. 10 with the pins 91 disengaged from the pawls. If the pawl-releasing plate is moved to the left Figs. 6 and 10 the pins 91 will engage the pawls and carry them out of engagement with the ratchet 76. This disengaging movement occurs when the nose 63 rides up on the high part of the cam rib 59 as the long-stitch cam is started in operation so that while the long stitches 1 are being formed the pawls 77 are out of engagement with the ratchet 76.

The feed cam 71 is, however, prevented from being returned to the full line position by the spring 84 during the formation of the long stitches by the operation of the stop member or brake 81 as above stated. This brake 81 is released from its engagement with the ratchet 76 by a cam projection 120 formed on the long stitch cam 33. It will be remembered that the brake 81 is carried by an arm 82 of a yoke 83 which is loosely mounted on the shaft 37. This yoke is formed with another arm 121 which carries a pin 122 that normally engages the peripheral portion of the cam 33. The cam 33 makes one rotation for the formation of the series of long stitches and just before it completes its rotation, that is, just before the long stitches are completed, the cam projection 120 engages the pin 122 and swings the arms 121 and 82 of the yoke outwardly thus releasing the brake 81 from the ratchet. This is the position of the parts shown in Fig. 16. As soon as this occurs the ratchet is released and the spring 84 returns the ratchet and feed cam from the dotted line to the full line position Fig. 16. When the cam 33 completes its rotation 130

thus terminating the formation of the long stitches 1 the nose 63 drops into the notch 60 and at the same time the cam 120 passes out of engagement with the pin 122. As a result of the latter operation the brake 81 is allowed to resume its operative position under the influence of a spring 123 and the dropping of the nose 63 into the notch 60 allows the arm 62 to move upwardly and the arm 88 to move to the right thus releasing the pawl-releasing plate and allowing it to move into its inoperative position under the influence of the spring 95. This movement of the pawl-releasing plate permits the spring-pressed pawl 77 to drop into operative engagement with the ratchet 76.

It will be remembered that when the nose 63 of the lever arm 62 drops into the notch 60 at the end of the long stitches the link 73 is raised thereby clutching the short-stitch cam 52 to the drive shaft 31 and as at the same time the pawls 77 are brought into operative engagement with the ratchet 76 the continued operation of the machine will actuate the short-stitch cam thus forming the short stitches as above described.

It will be remembered that the long-stitch cam 33 is provided with a closed cam groove 34 in which the roll 35 operates. In order 30 to permit the slow feeding of the work from one end to the other of the long stitches while the short stitches are being formed the groove 34 of the long stitch cam 33 is provided with a wide portion 96 so situated that when said 35 cam comes to rest at the end of the long stitches the roll 35 will be in the wide portion. This wide portion allows the swinging movement of the arm 36 necessary for the feeding movement while the short stitches 40 are being formed.

The feeding movement of the work clamps while the short stitches are being formed is accomplished by a spring 97, one end of which is connected to the arm 36 and the other end of which is connected to a lever or arm 99 that is loosely mounted on the shaft 37. The end of the arm or lever 99 carries a roll which operates against a cam face 100 that is rigid with the cam member 33. This cam 50 face is concentric throughout the greater portion of its extent but is provided with a rise 101, the latter being situated to engage the arm 99 just as the cam 33 is brought to rest. As the rise 101 passes under the arm 99 the latter is swung inwardly somewhat and the spring 97 is placed under tension, said spring 55 tending to swing the arm 36 inwardly and through the connections 40, 41 and 42 tending to swing the work clamps from the full to the dotted line position Fig. 16. This is the spring which holds the lever 72 against the feed cam 71 and, therefore, as the feed cam 71 is fed from the full to the dotted line 60 position Fig. 16 the spring 97 will cause a

corresponding feeding movement of the work clamps.

In order to produce a proper tack or bar it is desirable that the long stitches 1 should be laid centrally of the short stitches 2 and to thus center the work clamps so far as their jogging movement longitudinally of the arm 4 is concerned while the long stitches are being formed I have provided the following mechanism.

The arm 80 of the elbow lever 54 is provided with a hooked extension 102 that is adapted to engage the lower end of a lever 103 pivoted to the frame at 104. This lever 103 has a projection 105 thereon which operates with a projection 106 on the link 73 to center the work clamp during the formation of the long stitches. It will be remembered that the arm 80 of the elbow lever 54 is acted upon by a spring 56 which tends 85 normally to hold the work clamps at one extreme limit of their movement in a direction longitudinally of the arm 4. When the long-stitch cam 33 is at rest and the nose 63 is in the notch 60, as shown in Fig. 1, the link 73 90 will be in its elevated position and at this time the projection 106 thereon is above and out of alignment with the projection 105 as shown in Fig. 3. When, however, the long stitches are being formed and the cam 33 95 has been turned so that the high part of the cam rib 59 is engaging the nose 63 the link 73 will be in its lowered position shown in Fig. 19 and when in this position the projection 106 thereon is lowered into a position 100 opposite the projection 105 and said projections limit the lateral swinging movement of the work clamps due to the operation of the spring 56 and hold them in their central position.

As soon as the long stitches have been completed and the long-stitch cam 33 has come to rest with the notch 60 opposite the nose 63 the spring 70 will raise the link 73 thus withdrawing the projection 106 from behind the projection 105. Therefore, when the short-stitch cam is set in operation the elbow lever 54 is permitted to have its full swinging movement.

The machine is also provided with means 115 for automatically bringing it to rest after the short stitches 2 have been completed. I have above referred to the clutch by which the pulley 10 is coupled to the shaft 11 and to the clutch-actuating rod 13 by which the clutch is actuated. This rod is formed with an extension 107 having a shoulder 108 that is adapted to be engaged by a latch member 109 when the rod is moved inwardly to throw the clutch into engagement.

This latch member 109 is pivotally mounted on the arm 121 of the yoke 83, it preferably being pivoted on an extension of the pin 122. Said latch is also acted on by a spring 124 which tends normally to move it 120

inwardly into engagement with the shoulder 108. This latch is provided with a rod 125 on which is slidably mounted a releasing dog 126, the latter having a spring 127 connected thereto which normally holds it separated from the latch as shown in Figs. 11 and 14.

When the clutch rod 13 is moved inwardly to clutch the driving pulley 10 to the driving shaft 11 the shoulder 108 will be carried inwardly beyond the latch 109 and the latter will snap over the shoulder thus locking the clutch in its operative position. The clutch is released by means associated with the feed 15 cam 71, said means being so arranged that when the feed cam has completed its feeding movement the latch member 109 is disconnected from the shoulder 108 thus allowing the clutch spring to disconnect the 20 driving clutch.

This clutch-releasing means comprises a cam member 128 provided with a cam projection 129. Said cam member is adjustably secured to a collar 130 that is rigid with the 25 feed cam 71 and the ratchet 76 by means of a screw 131 which extends through a slot in the cam member 128. This cam member with its clutch-releasing nose 129 is so positioned that when the feeding cam 71 is in the full 30 line position Fig. 16 the nose will be in substantially the position shown in Fig. 14. As the feed cam 71 is fed forwardly for formation of the short stitches the cam-releasing member 129 will be moved from the position shown in Fig. 14 to that shown in Fig. 35 15. As it moves into the position shown in Fig. 15 the cam projection 129 engages the dog 126 and slides it forwardly on the rod 125 until it engages the end of the latch 109 as shown in Fig. 15. As the releasing cam 129 continues its movement the latch 109 will be swung outwardly into the dotted line position Fig. 15 thereby becoming disengaged from the shoulder 108 and allowing the clutch 40 spring 14 to disengage the driving clutch. As soon as this occurs the spring 127 will return the dog 126 to the full line position Fig. 14, thus carrying it back of the clutch-releasing cam 129. The latch 109 is thus 45 free to be swung into its operative position again as soon as the clutch-controlling rod 13 is moved to render the driving clutch operative.

This clutch-releasing cam 129 is provided 50 with an inclined face 133 and the dog 126 is also provided with an inclined face 134. Furthermore the dog can not only slide on the rod 125 but can turn thereabout so that when the feed cam 71 is released at the end 55 of the forming of the long stitches and is carried into the full line position Fig. 16 by the wound spring 84 the clutch-releasing cam 129 will simply ride under the dog 126, the latter swinging upwardly to allow the cam 60 to pass.

The clutch-disengaging lever 48 by which the long-stitch cam is unclutched from the driving shaft is normally held out of engagement when the driving clutch is disengaged. This is accomplished by a pin 136 on the clutch-controlling rod 13, which engages the end 137 of the lever 48, as shown in Fig. 4. When the clutch rod 13 is moved inwardly to render the main driving clutch operative the pin 136 is moved away from the extension 137 of the arm 48 thus allowing the latter to swing forwardly under the influence of the spring 139.

The lever 48 has pivoted thereto a strut member 140 which is so positioned and of such a size that when the lever 48 swings forwardly as shown in Fig. 17 this strut member will bear against the cylindrical face 141 of the cam member and when in this position it will hold the cam nose 50 away from and out of engagement with the head of the clutch pin 44 as shown in Figs. 4 and 17. As soon, however, as the long-stitch cam begins to turn in the direction of the arrow for the formation of the long stitches the friction of the strut member 140 against the face 141 will swing said strut member into the dotted line position shown in Fig. 18 thus allowing the cam nose 50 to be brought into position so that when the cam 33 completes its rotation the head of the clutch pin 44 will ride up the cam nose 50 as seen in Figs. 20 and 21 thus disengaging the long-stitch cam 33 from the cam shaft 31 as above described.

The herein described sewing machine is 100 constructed to form a group of underlying stitches and then to form a group of overlying stitches and is provided with means for varying the number of the overlying stitches without changing the length of the underlying stitches. Furthermore, by means of the construction herein shown it is possible to secure a uniform spacing of the overlying stitches regardless of the length of the underlying stitches.

It is also to be noted that the machine herein shown has a long stitch cam for reciprocating the work clamp to form the underlying stitches, and a second cam referred to as a "short stitch" cam for giving the work clamp a reciprocating movement in another direction to form the overlying stitches and a third cam, the feed cam, for giving a feeding movement to the work clamp during the formation of the overlying stitches.

I claim:

1. In a sewing machine, the combination with stitch-forming mechanism, of work-holding means, a cam shaft, a cam loose thereon for reciprocating the work-holding means in one direction, a second cam loose thereon for reciprocating the work-holding means in another direction, operative connections between each cam and the work-holding means, means to connect the first-named cam to the 125 130

cam shaft and then to disconnect it therefrom after it has performed a predetermined sewing operation, and means controlled by the first-named cam to connect the second cam to the cam shaft when the first-named cam is disconnected therefrom.

2. In a sewing machine, the combination with stitch-forming mechanism, of work-holding means, a cam shaft, a cam loose thereon for reciprocating the work-holding means thereby to form relatively long underlying stitches, a second cam loose on the cam shaft for reciprocating the work-holding means in another direction to form relatively short overlying stitches, means to connect the first-named cam to the cam shaft and then to disconnect it therefrom at the end of a predetermined sewing operation, and means controlled by said first-named cam to connect the second cam to the cam shaft when the first-named cam is disconnected therefrom.

3. In a sewing machine, the combination with stitch-forming mechanism, of work-holding means, a cam shaft, a cam loose thereon for reciprocating the work-holding means in one direction, a second cam loose thereon for reciprocating the work-holding means in another direction, operative connections between each cam and the work-holding means, means to connect the first-named cam to the cam shaft and then to disconnect it therefrom after it has performed a predetermined sewing operation, means controlled by the first-named cam to connect the second cam to the cam shaft when the first-named cam is disconnected therefrom, and means controlled by the second-named cam to bring the machine to rest.

4. In a sewing machine, the combination with stitch-forming mechanism, of work-holding means, a cam shaft, a long-stitch cam loosely mounted on the cam shaft, means operated thereby to vibrate the work holder thereby to form long underlying stitches, a short-stitch cam also loose on said cam shaft, means operated thereby to vibrate the work holder in another direction to form short overlying stitches, means to connect the long-stitch cam to the cam shaft and to disconnect it therefrom after a predetermined sewing operation, and means controlled by the long-stitch cam at the time it is disconnected from the cam shaft to connect the short-stitch cam to the cam shaft.

5. In a sewing machine, the combination with stitch-forming mechanism, of work-holding means, a cam shaft, a long-stitch cam loosely mounted on the cam shaft, means operated thereby to vibrate the work holder thereby to form long underlying stitches, a short-stitch cam also loose on said cam shaft, means operated thereby to vibrate the work holder in another direction to form short overlying stitches, means to connect the long-stitch cam to the cam shaft and to disconnect

it therefrom after a predetermined sewing operation, means controlled by the long-stitch cam at the time it is disconnected from the cam shaft to connect the short-stitch cam to the cam shaft, and means controlled by the short-stitch cam to bring the machine to rest. 70

6. In a sewing machine, the combination with stitch-forming mechanism, of work-holding means, a cam shaft, a long-stitch cam loosely mounted thereon and operating to vibrate the work-holding means to produce long underlying stitches, a short-stitch cam also loose on the shaft and operating to vibrate the work-holding means in another direction to form short overlying stitches, a feeding cam loose on the cam shaft for feeding the work during the formation of the short stitches, means to connect the long-stitch cam to the cam shaft and to disconnect it therefrom at the end of a predetermined sewing operation, means controlled by the long-stitch cam for connecting the short-stitch cam to said cam shaft when the long-stitch cam is disconnected therefrom, and means actuated by the short-stitch cam to operate the feed cam. 80

7. In a sewing machine, the combination with stitch-forming mechanism, of work-holding means, a cam shaft, a long-stitch cam loosely mounted thereon and operating to vibrate the work-holding means to produce long underlying stitches, a short-stitch cam also loose on the shaft and operating to vibrate the work-holding means in another direction to form short overlying stitches, a feeding cam loose on the cam shaft for feeding the work during the formation of the short stitches, means to connect the long-stitch cam to the cam shaft and to disconnect it therefrom at the end of a predetermined sewing operation, means controlled by the long-stitch cam for connecting the short-stitch cam to said cam shaft when the long-stitch cam is disconnected therefrom, and means actuated by the short-stitch cam to operate the feed cam. 90

8. In a sewing machine, the combination with stitch-forming mechanism, of work-holding means, a cam shaft, a long-stitch cam loosely mounted thereon and operating to vibrate the work-holding means to produce long underlying stitches, a short-stitch cam also loose on the shaft and operating to vibrate the work-holding means in another direction to form short overlying stitches, a feeding cam loose on the cam shaft for feeding the work during the formation of the short stitches, means to connect the long-stitch cam to the cam shaft and to disconnect it therefrom at the end of a predetermined sewing operation, means controlled by the long-stitch cam for connecting the short-stitch cam to said cam shaft when the long-stitch cam is disconnected therefrom, and means actuated by the short-stitch cam to operate the feed cam. 100

105

110

115

120

125

130

stitch cam is disconnected therefrom, means actuated by the short-stitch cam to give the feeding cam a forward feeding movement, a spring to return said feeding cam to its initial position, and means controlled by the long-stitch cam for disconnecting the feeding cam from its actuating means.

9. In a sewing machine, the combination with stitch-forming mechanism, of work-holding means, a cam shaft, a long-stitch cam loosely mounted thereon and operating to vibrate the work-holding means to produce long underlying stitches, a short-stitch cam also loose on the shaft and operating to vibrate the work-holding means in another direction to form short overlying stitches, a feeding cam loose on the cam shaft for feeding the work during the formation of the short stitches, means to connect the long-stitch cam to the cam shaft and to disconnect it therefrom at the end of a predetermined sewing operation, means controlled by the long-stitch cam for connecting the short-stitch cam to said cam shaft when the long-stitch cam is disconnected therefrom, means actuated by the short-stitch cam to give the feeding cam a forward feeding movement, a spring to return said feeding cam to its initial position, means controlled by the long-stitch cam for disconnecting the feeding cam from its actuating means, and means controlled by the feeding cam to bring the machine to rest.

In testimony whereof, I have signed my name to this specification.

JOHN KIEWICZ.
